UNITED STATES PATENT OFFICE.

DAVID W. ODIORNE, OF ELIZABETH, NEW JERSEY, AND ERNST BROSEMAN, OF NEW YORK, N. Y., ASSIGNORS TO SAID ODIORNE.

PINKING-MACHINE.

SPECIFICATION forming part of Letters Patent No. 288,847, dated November 20, 1883.

Application filed May 21, 1883. (No model.)

To all whom it may concern:

Be it known that we, DAVID W. ODIORNE, of Elizabeth, in the county of Union and State of New Jersey, and ERNST BROSEMAN, of the city, county, and State of New York, have invented a new and useful Improvement in Pinking-Machines; and the following is declared to be a description of the same.

The pinking or scalloping of the edges of fabrics is commonly done with a cutting-tool having an edge in outline the same as the scallop to be made, the cutting being done on a block of hard wood. Pinking-machines have also been made wherein the cutting-edge of the tool is formed upon the edge of a roller or disk, and the cutting of the fabric is done between this edge and the surface of a hard-metal roller, and these pinking-machines have been operated by hand or other power.

Our invention relates, essentially, to a swing-
ing and adjustable table to be operated in connection with a pinking-machine having a revolving die-cutter and metal roller; and the object of our invention is to pink or scallop the edges of fabrics, especially for umbrellas and parasols, and to do the same in a curved line that shall represent the arc of a circle of any desired radius. We employ a table, upon the surface of which there are hinged adjustable gages, the angle of which can be changed to suit the different sections of fabric used in umbrellas or parasols having different numbers of ribs, and said gages are adjustable lengthwise of the table, to accommodate sections of fabric for umbrellas, parasols, &c., of different lengths or sizes. The pivotal center of the table is adjustable by a hand-wheel and screw-rod, and we provide a nut upon the screw-rod and a companion block sliding upon a dovetailed way on the under side of the table. The screw-rod is supported by bearings formed in standards secured to a bed. The table rests upon curved ways supported by columns secured to the bed of the machine. The pinking-machine that we employ is made with a revolving disk-cutter operating against a hard steel roller, and these are revolved by toothed wheels and a pulley and belt.

In the drawings, Figure 1 is an elevation of our improved table. Fig. 2 is a plan of the

table and pinking-machine, and Fig. 3 is a cross-section at the line *xx* of Fig. 2.

A is the adjustable table for holding the fabric to be pined, and B is the pinking-machine. The V-shaped gages *a a'* are hinged together at *b*, and provided with holding-bars *c c'*, and said bars are slotted lengthwise. The table A has slots 1 2 3 formed in it, which are parallel to its length. The stems of the set-screws *d d'* pass through the slots 1 2 in the table A and in the holding-bars *c c'*, and the heads 4 bear against the under side of the table, and the set-screws clamp the parts to the table. The pin of the hinge-joint *b* has a head on its under side, bearing against the underside of the table-top, and said pin is in the slot 3. By loosening the set-screws *d d'* the V-shaped arms can be widened or contracted, or adjusted upon the surface of the table. We prefer to place a gage upon the table to indicate the length of the sections of fabric as cut by the machine.

The standards *e e'* are secured to a suitable bed, and they support the screw-shaft *f* and hand-wheel *g* upon the same.

The circular track *h* is supported upon standards 5 6 7 8, secured to the bed, and we provide metal blocks *i i'*, fastened to said track *h*, and surrounding the screw-shaft *f*. The supports for the bed are thus rigidly connected together.

There is a nut, *k*, upon the screw *f*, and said nut can be moved forward and backward by revolving the screw. There is a hole in the upper surface of the nut for the reception of the center-pin *l* upon the companion block *m*, and the block *m*, in its upper surface, has a dovetailed groove fitting the dovetailed way *o* on the under side of the table A. The block *m* has a projection-arm, *n*, extending to the edge of the table A, and a screw, *p*, passing through the same, for clamping said block *m* and the way *o* firmly together. The position of the nut *k* and block *m* and center-pin *l* upon the screw-shaft *f* determines position of the center-pin upon which the table A swings; consequently the arc of the circle upon which the edge of the fabric is scalloped or pined. To shift the position of this nut and block, we bring the table into the position shown in Fig. 100.

2, parallel to the screw-shaft *f*, and insert the pin *r* through the table *A* into a hole in the block *i*, securely holding the table in position. We then loosen the set-screw *p* and revolve the hand-wheel *g* and screw-shaft *f*, and move the nut *k* and block *m* and pivot of the table to the desired distance from the pinking-tools.

The pinking tool or cutter *s* is mounted upon a shaft, and its periphery runs in contact with that of the hard-metal roller *t*, and both tool and roller are operated by toothed wheels upon their respective shafts gearing together and driven by suitable toothed wheels and pulleys. These parts, being of well-known construction, do not require further description.

The pivot of the table is to be set as heretofore described to make the edge of the fabric on the required arc of a circle, and the gages *a a'* are set and clamped at the required angle to each other, and we take a piece of card-board of the same angle as the gages and of a length to almost reach the pinking-tool *s*, the edge of the card-board being an arc of a circle from the pivot of the table, and lay the same upon the table, between the gages *a a'*, the right-hand or curved end of the table being swung toward the operator. Sections of silk or other fabric of the proper size and similar angle and the desired number of thicknesses are laid on the card-board, and another piece of card-board corresponding to the bottom piece is laid on top. The operator, with his hands on the top card-board to press the fabric against the table, moves said table and the fabric toward the pinking-tool *s*, the fabric passes through, and the edge is cut with the desired figure, the table turning upon the pivot *l* as the revolving pinking-cutter and roller draw the fabrics through between them.

In Fig. 3 we have illustrated the manner of laying the fabric and card-boards between the arms *a a'*. It is important that the pivot upon which the table swings be slightly behind a vertical plane passing through the axis of the pink-

ing-tools and roller; otherwise the fabric will not be flat or remain in its place between the gages.

50

We claim as our invention—

1. In a machine for pinking fabrics, the combination, with the pinking-tool and roller, and mechanism for operating the same, of a table, *A*, circular track *h* for the same, blocks *k m*, center-pin *l*, means for operating and clamping said blocks, and the V-shaped adjustable gages *a a'*, substantially as and for the purposes set forth.

2. In a machine for pinking fabrics, the combination, with the pinking-tool and roller, and mechanism for operating the same, of a table, *A*, track *h* for the same, a center-pin, *l*, the V-shaped gages *a a'*, hinged together at *b*, the slotted holding-bars *c c'*, and set-screws *d d'*, substantially as and for the purposes set forth.

3. In a machine for pinking fabrics, the combination, with the pinking-tool and roller, and mechanism for operating the same, of a table, *A*, track *h* for the same, and gages upon the table, between which the goods to be pinked are laid, the screw-shaft *f* and the hand-wheel *g*, standards *e e'*, block *m*, nut *k*, and dovetail connection to the table *A*, the center-pin *l*, and screw *p*, as and for the purposes set forth.

4. In a machine for pinking fabrics, the combination, with the pinking-tool and roller, and mechanism for operating the same, of a table provided with an adjustable center or pivot, a track for the table to turn upon, and adjustable hinged gages that can be adapted to the varying sizes of fabrics, and between which gages said goods are laid while being pined, substantially as and for the purposes set forth.

Signed by us this 14th day of May, A. D. 1883.

D. W. ODIORNE.
E. BROSEMANN.
